(57) **CLAIM**

The ornamental design for a light fixture trim, as shown and described.

DESCRIPTION

This application is related to commonly owned concurrently filed U.S. design patent application Ser. No. 29/197,592.

FIG. 1 is a front elevation view of the light fixture of the present design, and the side and back elevation views being identical thereto; and,

FIG. 2 is a bottom plan view thereof.

The broken lines shown are for illustrative purposes only and form no part of the claimed design.
